UNITED STATES PATENT OFFICE.

JACOB LOOMIS, OF WHEELING, WEST VIRGINIA.

HOT MILL-ROLL.

1,130,911.

Specification of Letters Patent. Patented Mar. 9, 1915.

Application filed July 31, 1912, Serial No. 712,396. Renewed July 3, 1914. Serial No. 848,947.

To all whom it may concern:

Be it known that I, JACOB LOOMIS, a citizen of the United States, residing at Wheeling, in the county of Ohio and State of West Virginia, have invented a new and useful 5 Hot Mill-Roll, of which the following is a specification.

The object of my invention is to produce a roll which will have a longer average 10 working life than those now commonly in use.

The accompanying drawings illustrate my improved roll in comparison with rolls of the type shown in my Patent No. 831,727, 15 issued September 25, 1906.

Figure 1 is an axial section of a casting from which my roll may be machined; Fig. 2 is a section on line 2—2 of Fig. 1; Fig. 3 a side elevation of the core around which 20 was cast the casting shown in Fig. 1; and Fig. 4 a transverse section of a hollow roll after surface cracks have developed.

In the operation of hollow rolls in rolling mills, for the production of sheet metal, it is 25 found that sooner or later very fine cracks will appear in the working faces. These fine cracks—in many instances so fine as to be almost undiscernible by the unaided eye—produce fine—or coarser—hair marks or 30 ridges in the sheets and thus make the product either uncommercial or low grade. These cracks in the rolls are, in general, substantially parallel with the axis of the roll and are most frequently first found in the 35 region of the plane indicated by the core-box division mark left by the core around which the roll was cast. As is well known, these rolls are cast in molds having the axis of the roll (the core) vertical and the molten 40 metal is introduced tangentially near the bottom of the mold. The main body of the mold contains a chill along that portion of its length which is to be the sheet-rolling portion, and the molten metal therefore 45 cools more slowly adjacent the core. It is my opinion that, during this cooling, solidification (*i. e.*, contraction) stresses are set up in the metal immediately adjacent the core which are tangential to the inner 50 surface of the cast body and that those stresses result in minute cracks (or weaknesses tending to cracks) which extend lengthwise of the body substantially parallel with its axis and extend into the body in minute V's 55 which are substantially normal to the interior of the roll, as indicated at 10, 10 in

Fig. 4, on an exaggerated scale. There will be many of these minute cracks in substantially radial planes so that the roll may be analyzed as a barrel consisting of a plurality 60 of associated staves. When this roll is used it is, of course, subjected to enormous pressures in axial planes and therefore in substantial coincidence successively with the radial planes of the cracks 10. Ultimately 65 the initial cracks 10 are extended into cracks 11 which lead to the working surface 12. This further cracking of the roll is, in my opinion, the result of the repeated coincidence of the crack-planes with the pressure 70 plane and I have avoided the difficulty in the following manner. Instead of providing a core having a surface of revolution, as is the practice at present, I provide a core 13 having a surface composed of a plurality of 75 adjacent helical ribs 14. The main body of the core may be of substantially uniform diameter but I prefer to continue the teachings of my Patent No. 831,727 and make the main body of the core of larger diameter at 80 its middle, thus making each rib 14 a helix of decreasing radius at both ends.

When the roll 15 (Figs. 1 and 2) is cast around such a core there will, of course, be formed adjacent helical channels 16 within 85 the roll and, as a result of the cooling stresses, the minute cracks 10', which are unavoidably formed, will be normal to the surfaces of the channels and, instead of lying in radial planes relative to the axis of 90 the roll, will be in helices. As a consequence, these cracks can never be brought into substantial coincidence with the pressure plane but will always lie diagonally with relation to that plane and the rolling pressure will 95 not tend to further extend the initial cracks.

I claim as my invention:

1. A roll having an axial chamber whose surface is formed by adjacent helical channels of decreasing radii at both ends. 100

2. A roll having an axial chamber whose surface is formed by adjacent helical channels. 105

3. A roll having an axial chamber whose surface is a surface other than of revolution and is of less average diameter at both ends than in the middle. 110

4. A roll having an axial chamber whose surface is provided with grooves which intersect at an angle any plane drawn through the axis of the roll. 115

5. A roll of cast metal, said roll being

hollow, and the internal surface comprising inwardly projecting integral ribs having a general direction at an angle both to the axis of the roll and a plane at right angles thereto.

In witness whereof, I have hereunto set my hand and seal at Wheeling, West Vir-

ginia, this 20th day of July, A. D. one thousand nine hundred and twelve.

JACOB LOOMIS. [L.S.]
